UNITED STATES PATENT OFFICE.

JAMES WHITTEMORE, OF DETROIT, MICHIGAN, ASSIGNOR TO THE LIBBEY-OWENS SHEET GLASS COMPANY, OF TOLEDO, OHIO, A CORPORATION OF OHIO.

APPARATUS FOR DRAWING SHEET GLASS.

1,425,225.

Specification of Letters Patent. Patented Aug. 8, 1922.

Application filed March 2, 1921. Serial No. 449,092.

To all whom it may concern:

Be it known that I, JAMES WHITTEMORE, a citizen of the United States, residing at Detroit, in the county of Wayne and State 5 of Michigan, have invented new and useful Improvements in Apparatus for Drawing Sheet Glass, of which the following is a specification.

This invention relates to the art of drawing sheet glass from a bath of molten glass, and more particularly is an improvement on the apparatus disclosed in the patents to Colburn, 1,248,809, issued Dec. 4, 1917, and Re. 14,794, reissued Jan. 27, 1920. The 10 same improvement is also adapted for use with horizontal sheet drawing devices, as shown in my copending application, Serial Number 336,875, filed Nov. 10, 1919, of which this present application is a division 15 in part.

In the apparatus disclosed by the Colburn patents, a sheet of glass is drawn vertically from a bath of molten glass, and is then bent laterally over a cooled bending roll and 20 carried away horizontally through a suitable drawing mechanism and leer. At each edge of the sheet, adjacent the drawing point, is a pair of cooled edge rolls, between which the edge portion of the sheet is drawn 25 to form the same. In the patents referred to, these edge rollers are driven at a peripheral speed less than the linear speed at which the sheet is being drawn, so that a down pull or drag is made upon the edge 30 portions of the sheet to stretch them tight between the source and the bending roll.

This dragging action, together with the cooling effect of the water-cooled rollers, serves to overcome the natural tendency of 35 the sheet to narrow as it is drawn upward. I have discovered that it is unnecessary, and sometimes undesirable to drive these 40 rollers, but that on the contrary they may be used as idlers and driven from the sheet 45 itself as it is drawn therebetween. The friction of the rollers and co-operating parts, furnishes the necessary drag on the sheet 50 edges, and this friction may be supplemented and controlled by an adjustable friction brake on one or both of the roller shafts. I also contemplate using an improved form of edge roll, having a series 55 of peripheral grooves to engage the glass

sheet and further counteract the tendency to narrow.

The invention will be better understood from the following detailed description and drawings of two different glass drawing systems with which my improvement is adapted for use.

In the accompanying drawings:

Fig. 1 is a rear elevation of a sheet being drawn vertically, my improved edge rolls being shown complete at one side of the sheet, and partially broken away at the other.

Fig. 2 is a plan of the edge rolls at one side of the sheet, the sheet being shown in horizontal section.

Fig. 3 is a vertical section through a portion of the improvement, taken substantially on the line 3—3 of Fig. 2. Part of one gear is broken away to disclose the brake.

Fig. 4 is a detail of one of the edge rolls and its shaft, partly in section to show the internal water-cooling system.

Fig. 5 is a detail showing a different form of roll that may be used, and

Fig. 6 shows a central vertical longitudinal section through a horizontal sheet drawing apparatus with which my improved rolls are used.

Referring first, to the apparatus shown in Figs. 1 to 4, inclusive, a sheet of glass 1, is drawn upwardly from the molten glass 2 in receptacle 3, and is then bent horizontally over bending roll 4. This merely indicates conventionally the system set forth in detail

in the Colburn patents referred to above, and need not be further described. A pair of edge rolls 5 engage each edge of the sheet near its source, and it is between these rolls

that the sheet edge is drawn and formed. The supporting and cooling mechanism for these rolls is substantially the same as used in the prior Colburn structure already referred to, except that the driving connections are omitted and an adjustable friction

brake substituted therefor. Each metallic roll 5 is carried at the end of a somewhat long hollow shaft 6 or 6' which extends out over the side portion of the pot and heating chamber 7. The roll 5 is also hollow, and within the roll and the shaft 6, extends a smaller pipe 8, through which

a constant flow of cold water, or other fluid, is forced into the roll 5, from which it flows out through the shaft 6, as indicated by the arrows in Fig. 4.

- 5 At 9 is shown a horizontal angle bar support, to which a supporting block 10 is clamped in the desired position, longitudinally of the bar, by bolts 11. The block 10 has an undercut groove 12, on the inside of a shoulder 13 at one side of the block, and at the other side is an upwardly inclined flange 14. The supporting bracket 15 for the shafts 6 is adjustably carried on the upper face of block 10, one side of the bracket 15 having a flange 16 engaging in the groove 12, while the other side of the bracket is engaged by bolts 17, screwing through the flange 14, all as shown in Fig. 3. After loosening the bolts 17, the bracket 15, together with the entire edge forming assembly carried thereby, may be adjusted transversely of the pot or receptacle, so as to properly engage the sheet edge, after which by tightening the bolts 17, the assembly is locked securely in place. One of each pair of shafts 6, 6' is journaled in a fixed bearing 18 projecting upwardly from bracket 15. Preferably roller bearings (not shown) are provided for the shafts 6 and 6'. The other shaft 6' of the pair is carried by a bearing 19, which has a vertical pivot pin 20 journaled in bracket 15. This pivot 20 allows shaft 6' to be swung laterally with respect to the companion shaft 6, so that the rolls 5 may be disengaged from the sheet when desired. A spring 21 is confined between a downwardly projecting finger 22 on bearing 19, and an adjusting screw 23, mounted in the bracket 15. This spring, which is on the outer side of pivot 20, serves to normally press the two rolls 5 toward one another and hold them yieldingly against the sheet edge. Stop screw 24, mounted in bracket 15, and adjustable against the outer side of finger 22, limits the possible proximity of rolls 5 to one another.
- A pair of engaging gears 25, carried by shafts 6, 6', cause them to rotate equally and in unison. Secured to the shafts 6, between gear 25 and bearing 18, is a brake drum 26, encircled by a strap brake 27. The ends of the brake band 27 are carried by a rod 28 secured in bracket 29 projecting from bearing 18. One end of band 27 is pressed yieldably toward the other end by spring 30 confined between the band end and an adjusting wheel 31. By properly adjusting the tension of spring 30, by means of wheel 31, the drag of brakeband 27 on drum 26, may be varied as desired. The inherent friction in the rotating shafts and gears may sometimes be found to provide sufficient drag on the glass sheet, in which case the brake is not used at all.

At the outer ends of shafts or pipes 8 and 6, are secured suitable connections, indicated generally at 32 and 33, for providing for the inflow and outflow of the cooling liquid. A handle 34, having a removable pipe extension 35, is secured to the pivoted bearing 19 for shaft 6' to facilitate the disengagement of this shaft and roll from the sheet of glass 1, against the resistance of spring 21.

It is to be understood that the mounting described above for a pair of the idler rolls 5, is merely one approved form, and that many other variations of this mounting equally suitable for the purpose may be devised. The present invention resides in using these rolls as idlers and adding a brake to adjust the resistance of the rolls as may be found necessary.

The preferred form of roll 5, as shown in Figs. 1, 2 and 4 is provided with a series of peripheral grooves and ridges 36 and 37, (see Fig. 4). These engage the molten glass as the sheet is being drawn and grip the same to counteract the narrowing tendency of the sheet. In Fig. 5 is shown the form of knurled rolls 38 now used in the Colburn process, and it is to be understood that this form of knurled roll is likewise adapted for use with the idler roll assembly above described.

In Fig. 6 is shown a horizontal sheet drawing apparatus, in which the glass sheet 39 is drawn off from a heated slab 40, and stretched under a flattening roll 41, by means of a drawing mechanism 42. This mechanism is described in detail in my pending application Serial Number 336,875, above noted, of which this application is a division in part, and in which the idler edge rolls here claimed were first disclosed and claimed. The edge rolls indicated at 43 in Fig. 6, are of substantially the same form as those already described in connection with the vertical drawing mechanism, with some alterations made in the details of the supporting mechanism to adapt them to a horizontal drawing machine. The principle of operation is the same as with the vertical machine, the drag on the sheet serving to preserve the width of the sheet.

While I have illustrated but two forms of sheet drawing mechanism, it is to be understood that these are shown merely as examples, and that my improved idler edge rolls may be used with other systems of sheet drawing, whether the sheet be drawn up, down or horizontally.

I claim:

1. In a glass drawing apparatus, means for drawing a glass sheet from a mass of glass, and pairs of edge rolls engaging the sheet edges, adapted to be driven by the sheet passing between the rolls.

2. In a glass drawing apparatus, means

for drawing a glass sheet, pairs of idler rolls engaging the sheet edges, and means for cooling the rolls.

3. In a glass drawing apparatus, means for drawing a glass sheet, pairs of idler rolls engaging the sheet edges, and means on the rolls for holding the sheet from drawing inward.

4. In a glass drawing apparatus, means for drawing a glass sheet, pairs of idler rolls engaging the sheet edges, and means for frictionally retarding the rolls.

5. In a glass drawing apparatus, the combination with means for drawing a glass sheet, of pairs of cooled idler rolls engaging the edges of the sheet.

6. In a glass drawing apparatus, the combination with means for drawing a glass sheet, of pairs of cooled, circumferentially grooved, idler rolls, engaging the edges of the sheet.

7. In a glass drawing apparatus, means for drawing a glass sheet from a mass of molten glass, and a pair of idler rolls engaging each edge of the sheet at its source.

8. In a glass drawing apparatus, means for drawing a glass sheet from a mass of molten glass, and a pair of cooled idler rolls engaging each edge of the sheet at its source.

9. In a glass drawing apparatus, means for drawing a glass sheet from a mass of

molten glass, and a pair of cooled idler rolls, near the source of each edge of the sheet, between which the sheet edge is drawn.

10. In a glass drawing apparatus, means for drawing a sheet of glass from a mass of molten glass, and a pair of idler rolls near the source of each edge of the sheet between which the sheet edge is drawn, and means for frictionally retarding each pair of rolls.

11. In a glass drawing apparatus, means for drawing a sheet of glass from a mass of molten glass, a pair of idler rolls near the source of each edge of the sheet between which the sheet edge is drawn, gears connecting the rolls whereby they are compelled to rotate equally and in opposite directions, and means for cooling the rolls.

12. In a glass drawing apparatus, means for drawing a sheet of glass from a mass of molten glass, a pair of idler rolls near the source of each edge of the sheet between which the sheet edge is drawn, gears connecting the rolls whereby they are compelled to rotate equally and in opposite directions, means for cooling the rolls, and means for frictionally retarding each pair of rolls.

Signed at Santa Barbara, in the county of Santa Barbara and State of California, this 23rd day of February, 1921.

JAMES WHITTEMORE.
